DESIGN FOR A GOLF PRACTICE DEVICE

William E. Kohl, Cleveland, Ohio

Application September 7, 1939, Serial No. 87,081

Term of patent 14 years

To all whom it may concern:

Be it known that I, William E. Kohl, a citizen of the United States, residing at Cleveland, in the county of Cuyahoga and State of Ohio, have invented a new, original, and ornamental Design for a Golf Practice Device, of which the following is a specification, reference being had to the accompanying drawing, forming part thereof.

I claim:

The ornamental design for a golf practice device, as shown.

WILLIAM E. KOHL.
